UNITED STATES PATENT OFFICE

2,429,569

GEAR DRIVEN SOCKET WRENCH.

Edwin S. Stewart, Spokane, Wash.

Application November 6, 1943, Serial No. 509,224.

2 Claims. (Cl. 81—57)

1

The present invention relates to certain new and useful improvements in a gear driven socket wrench for turning bolts and nuts, and is particularly directed to providing a ratchet wrench in which the ratchet handle can be operated about an axis which is at right angles to the axis of the bolt and also offset towards the workman, so as to provide more freedom of movement in turning nuts and bolts which are so located as to limit the movement of the usual ratchet handle commonly used with the interchangeable socket wrenches which are in widespread general use.

The invention interposes a pair of spiral gears between the usual ratchet handle and its wrench socket, and is so constructed that vertical bolts or their nuts can be turned by operating the ratchet handle in a vertical plane instead of in a horizontal plane as is usually required.

With the present invention the ratchet handle always operates in a plane parallel to the axis of the bolt, and in the case of horizontal bolts, the plane of operation may be vertical, or horizontal, or in any inclined plane parallel to the horizontal axis of the bolt, thus enabling the workman to operate the wrench in whatever plane that affords the greatest convenience for efficiency and speed. In like manner with vertical bolts, the vertical plane of operation can be oriented to whatever position affords the greatest facility for working.

In any instance with the present invention, the ratchet handle operates in a plane at a convenient distance away from the axis of the bolt, and affords greater freedom of movement when the bolt is situated in inside corners or other inconvenient locations which would otherwise limit the movement of the usual ratchet handle.

The accompanying drawings illustrate the nature and principle of the invention, and show the best form that I have thus far devised for carrying the invention into actual practice.

Fig. 1 is a plan view of the invention, partly in section, and including the ratchet handle and an adapter socket therefor.

Fig. 2 is a vertical longitudinal section through the center of the invention, a part being removed.

Fig. 3 is a horizontal section through the center of the invention, parts being removed.

As shown in the drawing, the invention provides a gear block C which has a horizontal bore H and a vertical bore V, which inter-communicate with each other. Disposed in the horizontal bore H is a spiral gear D rigid upon the shaft 2 which has one end journaled in the gear block C and its opposite end 3 is stepped down and journaled in a bushing 4 which is fitted into the

2

horizontal bore H and secured in any suitable manner, as for instance by set screws such as R, one above and one below. The outer end of this shaft is squared as indicated at 12. Disposed in the vertical bore V, is a spiral gear 7 which meshes with the aforesaid gear D. This gear 7 is rigid upon a shaft having reduced portions 8 and 9 and squared ends 10 and 11. These reduced portions 8 and 9 are mounted in the flanged bushings 6 and 5 which are fitted into opposite ends of the vertical bore V and held in place in any practical manner, as for instance, these bushings may be fixed to the shaft by a pin or set screw as illustrated at P, in which case the bushings turn with the shaft and afford an enlarged bearing surface within the vertical bore V. If desired the pin P may be omitted and the bushings 5 and 6 held in place by set screws in the same manner as just described for the bushing 4; or, all three of these bushings may be threaded into their respective bores, if desired.

Rigid with the block C is a threaded rod 16, which has an enlarged boss 15 adjacent the block C. A collar 17 is rotatably mounted on the boss 15, and this collar has an arm 18 which carries a tube 20 in which there is slidably mounted a stem 21 having an enlarged head 22 which is preferably provided with a non-metallic facing X of some such material as rawhide, or fibre, or plastic. A thumb-screw 19 is threaded into the opposite end of the tube 20, so as to provide a stop for the stem 21 and also to urge the same forward as required. If desired this stem 21 may be provided with the well known friction catch consisting of a spring urged pin or ball.

A hollow handle E is threaded onto the rod 16, and this handle has an enlarged head F which bears against the collar 17 so as to hold the collar in any required position of rotation upon the boss 15. The outer end of the handle E has a bore 23 which corresponds to the stem 21 so that when this stem is removed it can conveniently be inserted into the bore 23 readily accessible for the next instance of use.

The forward end of this handle E is provided with a recess K which corresponds with the boss 15 and when the collar 17 is removed, the handle can be screwed up until its head F seats against the gear block C, so that the tool can be used either with or without the brace device collectively indicated at B and which is removed in Fig. 3.

The gear D is used to drive the gear 7, and in Fig. 1 there is shown at W, the well known ratchet handle having a square stud M which may be

connected to the squared end 12 by means of the illustrated adapter U which has squared openings in each of its ends. Thus the ratchet handle W can be used to turn the drive gear D in either direction and thereby rotate the gear 7 accordingly. As shown in Fig. 2, a wrench socket such as S can be applied to either of the squared ends 10 or 11 and used to turn a bolt or nut as the case may be. The purpose of providing the two squared ends 10 and 11 is so that the tool can be used either above or below a surface without turning the tool upside down, which would bring the ratchet handle into left hand position. If the workman be left handed, then he can position the tool so that the ratchet handle is on the left side, and then the tool can be used either above or below a surface without turning it over so as to make it right handed.

Where there is a series of bolts near a wall, the brace device B is used to bear against the wall and hold the tool in fixed position while turning the bolts or their nuts, the thumb screw 19 being employed to move the stem 21 forward so that the facing X contacts the wall; whereupon the tool can be used upon the whole series of bolts, with added convenience to the workman. This brace device can be positioned on either side of the tool by rotating the collar 17 the required amount and then holding it in position by screwing the handle E up tight. In any instance where the brace device is not used, it may be turned to the position shown in Fig. 2, and the stem 21 can be inserted into the bore 23; or else the brace device can be entirely removed as illustrated in Fig. 3.

It will be seen that the invention provides a gear driven socket wrench which can be operated by the conventional ratchet handle, and that any selected wrench socket can be used upon either of the square studs 10 or 11, and that the ratchet handle W is situated a convenient distance away from the work so as to provide freedom of movement. This enables the workman to operate the ratchet handle with far greater speed and also with longer strokes, thus affording efficiency and convenience. Also the tool can be operated in situations where there is not room enough for operating the usual ratchet wrench.

The invention may be made with any suitable gear ratio. The illustrated spiral gear D is essentially a multiple start worm, and it will be understood that the spiral gear 7 may be supplanted by a worm gear, if desired.

As here shown the ratchet handle W is provided with the conventional stud M which fits wrench sockets such as S; for which reason the adapter U is employed when this form of ratchet handle is used with the gear drive of the present invention; however, the end of the shaft 3 may be provided with a square recess so as to engage the stud M directly. Some ratchet handles are made with an aperture instead of a stud, in which case the adapter U need not be used.

Any of the squared ends 10, 11, 12 or M may be provided with a friction catch such as the well known spring urged ball, and therefore this conventional expedient is not shown, as it is merely an optional convenience.

Where the brace device B is not desired, the

handle E may be made rigid with the gear block C in any suitable manner.

In the present disclosure, I claim as my invention:

- 5 1. A gear driven socket wrench comprising a gear block having a horizontal bore and a vertical bore inter-communicating therewith, a spiral gear upon a shaft rotatably mounted for operation in said vertical bore, a wrench socket upon the shaft of said gear, a spiral drive gear upon a shaft rotatably mounted for operation in said horizontal bore and meshing with the first said gear, a ratchet handle for turning the shaft of said drive gear, a threaded rod rigid with said gear block and disposed with its axis on a line transversely intersecting both of said gears at right angles to the axis of each of them and having an enlarged boss adjacent said gear block, a collar rotatably mounted on said boss, an arm extending radially from said collar, a slidably mounted stem carried by said arm and disposed in spaced relation along the side of said gear block and in offset parallel relation to the axis line of said threaded rod, and a handle threaded upon 20 said rod and holding said collar against said gear block, whereby said collar can be held at a set position of rotation and quickly released by a fractional turn of said handle relative to said threaded rod.
- 10 15 2. A gear driven socket wrench comprising a handle, a gear housing on the forward end of said handle, a pair of spiral gears journaled in said housing and in mesh with each other, the axis of said handle being disposed on a line transversely 25 intersecting both of said gears at right angles to the axis of each of them, a wrench socket turned by one of said gears, a ratchet handle for turning the other said gear, a collar rotatable around the axis of the first said handle, an arm extending 30 radially from said collar, a tube rigid with said arm and extending forwardly therefrom in spaced relation along the side of said housing and in offset parallel relation to the axis line of said handle, a stem slidably mounted in said tube, and a 35 screw threaded axially into said tube for urging said stem forwardly.
